US00D372883S

United States Patent [19]

[19]

[11] Patent Number: Des. 372,883

[45] Date of Patent: Aug. 20, 1996

[54] GEMSTONE

D. 334,154 3/1993 Benderly D11/89

[76] Inventor: Oded Adler, 550 S. Hill St. #1384, Los Angeles, Calif. 90013

[] Term: 14 Years

[21] Appl. No.: 36,041

[22] Filed: Mar. 10, 1995

[30] Foreign Application Priority Data

Sep. 12, 1994 [IL] Israel 23273

[52] U.S. Cl. D11/89

[58] Field of Search D11/1, 2, 26-29,
D11/89, 90; 63/2, 1, 32

[56] References Cited
